(57) **CLAIM**

The ornamental design for a lock body of a cable lock as shown and described.

DESCRIPTION

FIG. 1 is a top, left, and front perspective view of a lock body of a cable lock showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

Features illustrated as broken lines in the drawings form no part of the claimed design.
